UNITED STATES PATENT OFFICE

2,272,121

CARBON HOLDER FOR MANIFOLDING MACHINES

Louis Jensen, Chicago, Ill., assignor to United Autographic Register Co., a corporation of Illinois

Application April 15, 1940, Serial No. 329,791

2 Claims. (Cl. 282—3)

This invention relates to duplicating machines, and more particularly to an improved device for holding transfer material.

The primary object of the invention is to provide an improved holding blade for a carbon or transfer slip that will not catch advancing stationery at the register perforations.

A further object of the invention is to provide an improved form of transfer slip that may be easily anchored to the carbon holding blade and will have its corner portions cut-away with relation to the notches in the carbon blade so that the perforations in the stationery will not catch or tear the transfer slip.

The improved transfer slip holding device, while particularly adapted for use in an autographic register, may also be used in an Elliott-Fisher machine, a typewriter, or other duplicating machines using continuous-form stationery. Such stationery is usually provided with register perforations which have a tendency to catch and tear on interleaved blades or to catch and tear the rear edge portion of transfer slips anchored between the stationery. The present invention is to avoid these difficulties and provide an inexpensive carbon slip which may be readily replaced.

The invention is illustrated in a preferred embodiment in the accompanying drawing, in which—

Figure 1 is a broken plan view, partly in section, of an autographic register embodying the invention; Figure 2, a view similar to Figure 1 with a top stationery strip removed to expose the transfer slip; Figure 3, a broken sectional view, taken as indicated at line 3—3 of Figure 1; and Figure 4, a plan view of the holding blade.

In the embodiment illustrated, an autographic register 5 is shown with a supply compartment 6 from which stationery strips 7 may be drawn over a writing platen 8, in the well-known manner.

A carbon holding blade 9 is preferably made of thin steel and is pivotally mounted at one edge of the platen, as indicated at 10. The opposite side of the platen is provided with a loop or notch

11 so that the blade may be flexed upwardly and slipped into position. The blade is provided with a pair of V-shaped notches 12 which are rearwardly presented and are in alignment with register perforations 7a provided in the stationery.

The carbon or transfer slip 13 has a neck portion 14 which bridges the distance between the notches 12 in the blade. The corner portions 15 are cut-away on a bias which is in alignment with one edge of the adjacent V-shaped notch 12 in the blade 9. Preferably the rear end portion of the transfer slip with its neck 14 is uncarbonized or not covered with transfer material, so that the slip may be handled without soiling the operator's fingers.

In the drawing only one carbon slip is shown, but it will be understood that additional slips may be provided with supporting blades in superposed relation, if more than two stationery strips are to be used.

The foregoing detailed description has been given for clearness of understanding only, and no unnecessary limitations should be understood therefrom for some modifications will be obvious to those skilled in the art.

I claim:

1. A manifolding device, for continuous-form stationery strips provided with transverse pairs of register perforations, comprising: a thin 30 silent blade, adapted to be interleaved between the stationery strips, and having a pair of rearwardly presented V-shaped notches in alignment with the register perforations in the stationery; and a duplicating slip extending forwardly in interleaved relation with the stationery and having a narrowed rear end portion folded over said blade between said notches to anchor the slip against advancement with the stationery.

2. A device as specified in claim 1, in which 40 the folded anchoring portion of the carbon strip is of a width equal to the distance between the V-shaped notches and each rear corner portion of the duplicating slip is cut-away on a biased line forming a prolongation of one edge of the adjacent V-shaped notch in the holding blade.

LOUIS JENSEN.
